UNITED STATES PATENT OFFICE

2,098,771

CIRCUIT CONTROL DEVICE

William Bogue, Chicago, Ill.

Application May 8, 1936, Serial No. 78,617

2 Claims. (Cl. 179—2)

This invention relates to a circuit control device, and more particularly to a device adapted for use in connection with an ordinary telephone for controlling a power circuit independently of 5 the telephone circuit.

It is an object of the present invention to provide means controlled by the usual telephone receiver hook or support, whereby a radio or other electrically operated device may be automatically disconnected from its power source when the receiver is removed from the hook, and wherein the power circuit will be automatically closed when the receiver is replaced on the hook.

A further object is the provision of a so-called 15 extension cord having a combined attachment plug and receptacle at one end into which the connector cap or plug of a radio circuit may be removably inserted, and an automatic switch at the other end of the cord and arranged to be 20 automatically controlled by the movement of the telephone receiver hook or support.

A further object is to provide a device of the character described which will be cheap to manufacture, easy to install, and which will not easily 25 get out of order.

Further objects will be apparent from the specification and the appended claims.

In the drawing:

Figure 1 is a front elevation of the usual desk 30 telephone having the control switch attached thereto.

Fig. 2 is a vertical axial section through the control switch illustrated in Fig. 1.

Fig. 3 is a longitudinal sectional view through 35 the combined attachment plug cap and receptacle used on the extension cord.

Fig. 4 is a sectional view taken on a line substantially corresponding to line 4—4 of Fig. 3.

Fig. 5 is a diagrammatic view of the electrical 40 circuit and connections arranged for controlling a radio set or other electrically operated device.

Fig. 6 is a side elevation of a so-called cradle telephone having a control switch attached thereto.

Fig. 7 is a fragmentary view illustrating a 45 preferred form of switch plunger arranged to be removably positioned for operation by a telephone hook.

Fig. 8 is a side elevation of the switch and illustrates the method of attachment by means of a 50 vacuum cup.

Referring to the drawing in detail, the embodiment illustrated in Figs. 1 to 5, inclusive, comprises an ordinary desk telephone 1 having the 55 usual transmitter supporting column 2 and re-

ceiver hook 3, on which latter is removably supported a receiver 4. A control switch 5, which is preferably cylindrical, is positioned below the hook 3 and clamped to the column 2 by means of a suitable clamping member 5 6 and securing screw 7.

The switch is illustrated in detail in Fig. 2 and preferably comprises a cylindrical shell 8 of insulating material having a metallic sleeve 9 therein. The lower end of the sleeve 9 is closed 10 by means of an insulating plug 10 and the sleeve extends above the upper end of the insulating plug as illustrated.

The insulating plug 10 is provided with a center contact 11 having a threaded stand 12 extending through the insulating plug and provided at its lower end with a terminal 13 to which an electrical conductor 14 may be secured. The shell contact 9 is provided with a downwardly extending terminal 15 to which conductor 16 may 20 be attached. These terminals are suitably insulated and enclosed by means of a cap 8a threaded on the insulating shell 8.

The switch is provided with an upwardly extending plunger 17, the lower end being threaded 25 and having an insulating member 18 attached thereto. Spring contact members 19 are secured to the insulating member 18 by means of a contactor screw 20 and the upper ends of these spring members are in frictional contact with the shell. 30 This contactor screw 20 is arranged to complete the electrical connection between the shell 8 and the center contact 9 when the plunger is in the lowered position illustrated in Fig. 2. It will be apparent that by raising the plunger 17 the electrical 35 connection between the shell and center contact will be broken.

The plunger 17 may be connected to the telephone hook in any suitable manner, for instance, such as illustrated in Fig. 1, in which a sheet 40 metal arm 21 may be clamped or otherwise secured to the hook 3 between the receiver and the column 2, and the plunger 17 may be threaded therein and secured by means of a nut 22. A preferred method of coupling the switch plunger 45 to the receiver hook is illustrated in Fig. 8 wherein in the hook 3 is engaged in a slot 17a in the plunger.

The switch 5 is also positioned under the hook 3 so that when the receiver is on the hook, the 50 plunger will be in the lowered position shown in Fig. 2, and the circuit between the conductors 14 and 16 will be closed.

When the receiver 4 is removed from the hook, the automatic raising of the hook will lift the 55

plunger 17 and associated friction contacts 18 to the position illustrated in dotted lines in Fig. 2 and the circuit will be broken. It will be apparent that when the receiver is replaced on the 5 hook the circuit will again be closed.

The opposite ends of the conductors 14 and 16 forming the extension cord are secured to the terminals of a combined connector and receptacle 23 as illustrated in Figs. 3 and 4. This connector 10 comprises a base 24 having the usual connector blades 25 and 26 mounted thereon. Receptacle contacts 27 and 28 of the usual type are provided and the contact 27 is insulated from the connector blade 25 and is provided with a suitable terminal to which the conductor 14 is electrically connected. Receptacle contact 28 is electrically connected to the connector blade 26, as illustrated.

The electrical control circuit for controlling 20 the usual radio set by means of the telephone receiver is diagrammatically illustrated in Fig. 5, and it will be apparent that when the combined receptacle and connector 23 is inserted in the usual manner in the ordinary electrical outlet of 25 a power circuit, and a connector cap 29 on the extension cord of a radio set 30 is plugged into the receptacle 23, the radio may be operated from the power line in the usual manner.

The control switch 5 is preferably in series in 30 the power line. Therefore, whenever the receiver 4 is lifted from the telephone hook, the power line will be broken and will be automatically connected to continue the operation of the radio when the receiver is replaced on the hook.

35 Fig. 6 illustrates the application of the device to a so-called cradle telephone and in this application a sheet metal bracket 31 may be provided with depending ears 32 which are clamped to the movable support 33 on which the receiver 40 normally rests and which corresponds in function to the usual telephone hook. The plunger 17 of the switch 5 may be connected to the bracket 31 in the same manner as previously described 45 in connection with Fig. 1.

45 Fig. 8 illustrates a method of removably attaching the switch to a box telephone or to any other type of telephone presenting a surface capable of receiving and supporting a so-called vacuum cup. In this embodiment the switch 5 is provided with a clamp or supporting bracket 34 having an arm 35 to which is attached a vacuum cup 36. The cup is preferably of rubber and the switch may be easily attached by merely pressing the cup against a suitable surface on 50 the telephone below the hook 3.

While the invention has been described in connection with a radio set, it will be apparent that it is adaptable for controlling various types

of power operated devices, such as flat irons, ironing machines, washing machines, etc., which are often left connected during a telephone conversation with disastrous results.

5 It is sometimes desirable to provide a screw plug combined connector and receptacle instead of the blade type illustrated. The invention therefore contemplates the substitution of the usual screw shell contact for the blade 25 and the usual center contact for the blade 26. The 10 insulating base may be arranged to support these contacts so that the electrical connections may be as previously described herein.

15 Modifications may be made to adapt the invention to the various requirements, without departing from the spirit of the invention. It is therefore desired that the invention be limited only by the prior art and the scope of the appended claims.

Having thus described this invention, what is 20 claimed and desired to be secured by Letters Patent is:

1. In a circuit control unit an extension cord comprising a pair of conductors having a combined connector and receptacle at one end, said 25 connector comprising a base having a plug-in contact and a receptacle contact electrically connected in series, a second plug-in contact and a second receptacle contact in said base and insulated from each other, a switch connected in 30 series between said second contacts by means of said conductors, and means for mounting said switch on a telephone in cooperative relation with the usual receiver support, said switch being constructed and arranged to be opened and closed 35 by the normal operation of said receiver support.

2. A control extension cord unit for electrically 40 operated devices, comprising a combined plug-in and receptacle base having two receptacle terminals therein and two plug-in terminals extending therefrom, one of said receptacle terminals and one of said plug-in terminals being connected together to form a continuous conductor through said base, the other receptacle terminal and plug-in terminal being insulated from each other in 45 said base and electrically connected in series by an elongated extension cord conductor extending therefrom, a switch at the opposite end of said conductor and in series with said last-mentioned terminals, and means associated with 50 said switch for mounting said switch on a telephone adjacent the receiver support whereby said switch is automatically controlled by said support to open said switch when the telephone receiver is removed from said support and to close said switch when said receiver is returned to said support.

55 WILLIAM BOGUE.
